UNITED STATES PATENT OFFICE.

JOSEPH H. WRIGHT, OF NEW YORK, N. Y.

DESIGN FOR SHADE-CLOTH.

SPECIFICATION forming part of Design No. 36,102, dated October 7, 1902.

Application filed August 16, 1902. Serial No. 119,973. Term of patent 3½ years.

To all whom it may concern:

Be it known that I, JOSEPH H. WRIGHT, a citizen of the United States, and a resident of the city of New York, borough of Manhattan, in the county and State of New York, have invented and produced a new, original, and ornamental Design for Shade-Cloth, of which the following is a specification, reference being had to the accompanying drawing, forming a part thereof, which represents a plan view of a piece of shade-cloth embodying the features of my design.

The design consists of rows of shell-like figures, the figures spaced apart in one row being above the spaces between the figures

of an adjoining row, each figure consisting of a number of segmental nested lines of varying thickness.

Having thus described my invention, I claim as new and desire to secure by Letters Patent—

The ornamental design for shade-cloth herein shown and described.

In testimony whereof I have signed my name to this specification in the presence of two subscribing witnesses.

JOSEPH H. WRIGHT.
